UNITED STATES PATENT OFFICE.

PAUL FRIEDRICH HELLERMANN, OF HAMBURG, GERMANY.

DEVICE FOR STRETCHING PIECES OF TUBE.

Original application filed July 27, 1925, Serial No. 46,474, and in Germany February 9, 1925. Divided and this application filed January 21, 1927. Serial No. 162,660.

If insulated electrical conductors or cords are to be connected to a switch or a source of current or to an implement or utensil which consumes electric current, the end or ends of 5 the metallic conductors must first be laid bare. For this purpose it is necessary to remove for a suitable length the silk or other insulation. The usual consequence is that the fibrous ends of the insulation which still remains on the 10 conductor form a tangle which, if care be not taken, will gradually lead to further displacement of the insulation or to unraveling of the threads or fibres. That is, the insulation must be bound again at the bared portion not 15 only for the sake of appearances but in the interest of security. For this purpose there were heretofore used binding threads, insulating tapes or the like which were wound around the insulation and secured by adhesive or knotted. If the binding be not drawn 20 tight, there is no effective security against subsequent displacement of the insulation. Also knots and fastenings effected by adhesive readily give way. The like is true if bare 25 parts of electrical conductors the ends of which are wound together are to be insulated.

Now, the subject of the present application which is a division of my pending application Ser. No. 46,474 filed July 27, 1925, 30 is a device which is adapted to be used for binding such insulated conductors or bare electrical conductors requiring to be insulated. By means of this device a piece of rubber tubing or the like cut to a suitable 35 length and of minimum bore is stretched transversely in at least two different directions, and after insertion of the conductor as far as it is to be covered by the binding, or as far as the insulation is to extend the stretching 40 effort is discontinued to allow the tubing to tensionally grip the conductor. The bore of the tubing is, if possible, such that the piece of tubing not only embraces an end of the insulation as well as the adjoining bared portion 45 of the conductor, having sufficient tension to grip the naturally thinner end of wire.

In the accompanying drawing the device is shown in

50 Fig. 1 in plan, and in
Fig. 2 in side elevation.

Figs. 3 and 4 are an elevation and a plan of an accessory for use with the device shown in Figs. 1 and 2.

Figs. 5 to 13 illustrate the various stages of 55 operation in the use of the instrument.

Fig. 14 shows two conductor sections bound according to the invention.

The pliers-like instrument shown in Figs. 1 and 2 consists of two jaws *b* pivoted at *a* 60 and adapted to be moved apart by gripping together the handle members *c*. A spring *d* mounted on two curved guide members *e* fixed to the handle members urges the jaws towards one another. The jaws can be detained in the 65 position corresponding to the compressed position of the spring by a clasp member *f* comprising two arms and pivoted at *g* to one handle *c*, being subject to the influence of a spring *h*. The jaws *b* each carry one half of each 70 of two impaling pins *h* and *i* which are somewhat rounded at one end so that they can be readily introduced into the tubing. When the handles are brought together, the half portions of the impaling pins move apart. 75 The pin *h* is in toto thinner than the pin *i*. Associated with this instrument is the accessory shown in Fig. 3. The latter consists of a corrugated sheet metal plate or strip *m* from one lateral edge of which project two pins *n* 80 and from the other lateral edge of which project two pins *o*, the pins being parallel to a line constituting the generatrix of said arched portion. The pins *o* are spaced further apart than the pins *n*. If desired the corrugation 85 *k* may be curved to shorter radius near the pins *n* than near the pins *o*.

The mode of use of the instrument is as follows:

First, as shown in Fig. 5, the stretcher is 90 held in one hand while with the other hand a piece of tubing *p* is impaled on the split impaling pin *i*, being preferably slightly expanded or stretched. This piece of tubing is cut from a rubber tube the bore of which, 95 if to receive insulated conductors of 6 millimetres diameter, amounts to about 1½ to 2 millimetres, and the wall of which is sufficiently strong to permit the necessary expansion. When this is done, the handles *c* 100 are compressed so that the tubing is powerfully stretched in one direction. Then the accessory instrument *m* is inserted in the expanded tube, thus for example, the pins *o* are inserted the spacing of the pins *o* being 105 less than the spacing of the halves of the pin *i* when moved apart (Fig. 7). Then, as shown in Fig. 8, the instrument *m* is turned

through 90°, so that the tubing is stretched in two directions at right angles to each other. The instrument *m* can now be released without its returning to initial position. Guided by the corrugation *k* a cord *r* presenting a tassel *s* of insulation formed by exposing the bared ends of the conductors can now be introduced into the tubing which has been stretched in two directions—see Figs. 9 and 10. Then, as shown in Fig. 11, the instrument *m* is reversely turned through 90° into Fig. 7 position. The tube *p* now grips the conductor *r* at two sides and holds it securely. The conductor can thus be released and the instrument *m* withdrawn from the tube. Then the stretcher handles *c* are so released as to allow the halves of the pin *i* to come together (Fig. 12), the conductor *r* being now gripped by the tube and disengaged from the stretchers (Fig. 13). The binding operation is thus completed.

Such bindings are illustrated in Fig. 14. As shown, not only the insulated portion but also parts of the protruding wire ends are embraced by the tubing, though this is not necessary. Also bared conductor ends can be insulated by means of a piece of tubing applied in this way, or connected cords can be separatively sleeved by tubing as shown.

As is understood, the stretchers can be used for all cases where pieces of tubing require to be stretched.

I claim:—

1. A device for stretching pieces of tube particularly for the purpose of covering the

junction between the bared end and the insulated portion of an electrical conductor, comprising, corelative members including pliers having a pair of cooperating separable pins arranged substantially parallel with the axis of movement of said pliers, and a complementary spreading member having a trough-like portion adapted to lie out of the path of the projection bore of the tube to be stretched, when said member is in position, and having spaced pins extending longitudinally from one end of said trough-like portion.

2. A device for stretching pieces of elastic tubing particularly for the purpose of encompassing an electric conductor with said tubing under permanent tension, comprising pliers of the type in which the jaws open when the handles are pressed together, a pin projecting laterally from said jaws in a direction substantially parallel to the pivotal axis of said pliers, said pin being longitudinally divided forming mating halves, one carried by each jaw, and which move apart when said jaws are separated, a spreading member adapted to fit the space between said halves, and a latch comprising parts mounted on said handles engageable when said jaws are spread to hold the halves of said pin in a definite spread position in which said spreading member fits between them.

In testimony whereof I have signed my name to this specification.

PAUL FRIEDRICH HELLERMANN.
